UNITED STATES PATENT OFFICE

CHARLES LEA, OF BOSTON, MASSACHUSETTS, ASSIGNOR TO THE AUTOMATIC MER-
CHANDIZER INC., OF BOSTON, MASSACHUSETTS, A CORPORATION OF DELAWARE

VENDING MACHINE

Application filed August 2, 1927. Serial No. 210,095.

My invention relates to vending machines, and particularly but not exclusively to one having coin controlled mechanism.

The invention will be best understood from the following description when read in the light of the accompanying drawings of an example of the invention, while the scope of the invention will be more particularly pointed out in the appended claims.

10 In the drawings:—

Fig. 1 is a longitudinal section of a vending machine constructed according to the invention;

Fig. 2 shows a detail of the machine according to Fig. 1 on an enlarged scale with the parts in a different position;

Fig. 3 is a plan view of the parts shown by Fig. 2;

Fig. 4 is a section on the line 4—4 of Fig. 1;

Fig. 5 is a fragmentary section on the line 5—5 of Fig. 1;

Fig. 6 is a section on the line 6—6 of Fig. 4;

Fig. 7 is a view corresponding to Fig. 6 with the parts moved to a different position;

Fig. 8 is a section on the line 8—8 of Fig. 6;

Fig. 9 is a section on the line 9—9 of Fig. 4; and

Fig. 10 is a section on the line 10—10 of Fig. 9.

Referring to the drawings the submitted embodiment of the invention comprises a cabinet having the top 1, back wall 3, bottom 5, and side walls 7 constructed of suitable material, as for example wood, the upper portion of the front wall preferably being a glass plate 9 rendering the contents of the cabinet visible, the lower portion 11 of the front wall preferably being of metal.

Herein the back wall of the cabinet carries the member 13, preferably of metal, provided with end flanges 15 which carry the inturned portions 17. At the lower end of the member 13 are provided lips 19 which in conjunction with a bar 21 are adapted to support a stack of articles A to be vended.

Herein the articles are shown resting upon plates 23 interleaved between the articles,

the lowermost plate resting at opposite ends respectively upon the bar 21 and lips 19. As shown the plates 23 are notched at the sides thereof adjacent one end as indicated at 25 (Fig. 5), said notches engaging the inturned portions 17 of the member 13 so as to be guided thereby. As shown suitable guide bars 27 may be provided for guiding the articles which rest loosely upon the plates.

For disengaging the plates 23 from the bar 21 and lips 19 herein is provided a lever pivoted at 28 and having the flattened portion 29 fitting a slot 31 in the back wall of the cabinet, said portion 29 of the lever being formed integrally with and projecting laterally from a rod like portion 33 of the lever. As shown the portion 33 of the lever has a cylindrical head 35 adapted to enter the hole 37 in the lowermost of the stack of plates 23. Swinging the lever counterclockwise about 70 its pivot 28 will push the lowermost plate 23 of the stack to the left, as viewed in Fig. 1, which will disengage said plate from the lips 19 and permit it to fall as indicated by the plate in its dotted line positions in Fig. 1, the plate during falling being in engagement with the rod like portion 33 of the lever and with the flattened spring member 38 which affords a continuation of said lever so as to be guided thereby and to be stacked 75 at the bottom of the receptacle 39. As shown the flattened member 38 may be in the form of a spring removably engaged in the slot 39 at the end of the rod like portion 33 of the lever for disengaging the plates.

When a plate 23 is released from the bottom of the stack as above described it falls through a hole 40 in a plate 41 positioned below the stack and inclined downward toward the front of the cabinet, this hole being of about the dimensions of the plate 23 so that the article which is of greater dimension than the hole will be caught by the plate 41 and slid through the opening 42 in the front wall of the cabinet.

For actuating the lever for disengaging the plates 23 from the bottom of the stack herein is shown a plunger 45 which, through locking mechanism situated in the casing 47 and a connecting link 49, is adapted to move 100

the lower end of the lever to the right, as viewed in Fig. 1, against the tension of a spring 51 acting to return the parts to the position shown in Fig. 1 when the hand of the operator is moved from the plunger 45.

Herein above the uppermost plate 23 and resting thereon is a V-shaped bar 53, the apex of which is adapted to engage with the head 35 of the actuating lever (as shown by Figs. 2 and 3) when the uppermost plate of Fig. 1 is finally disengaged. This will prevent return of the lever from the position of Fig. 2 to the position of Fig. 1, and prevent further actuation of the device after the last article 15 is discharged from the cabinet.

Herein slidably mounted in the casing 47 is a pair of bars 55 held in spaced relation by means of a block 57 fixedly secured to said bars, while connected to said bars are the operating plunger 45 and link 49 hereinbefore referred to. Below the bars 55 at one end of the casing 47 is a slidably mounted plate 59 provided with a pair of longitudinally extending slots 61 (Figs. 4 and 10), while each bar 55 carries a pin 63 projecting into said slots, thus connecting the plate 59 to said bars for limited relative movement. Carried by the casing is a pawl or detent 65 having the depending portions 67 pivoted at 69 to a casing, the spring 71 urging the pawl against the lower surface of the bars 55 into the path of the right hand end of the plate 59, as viewed in Fig. 6.

As shown the bars 55 at the inner sides 35 thereof are provided with facing slots 73 and 75, the former of which, when the parts are in the position shown by Fig. 6, is in registry with a slot 77 leading to a coin receiving opening 79 formed in the exterior portion of the casing, the opening 79 being preferably cylindrical and of about the exact diameter of a coin C of predetermined size, as for example, a dime. The block 57 as shown is provided with a spring pressed pawl in the form of a ball 81 adapted to engage with openings or recesses 83 and 85 formed in the plate 59, the purpose of which is to cause the plate to move with the bars. With the parts in the position shown by Fig. 6, assuming the coin C has been inserted and the plunger is pressed inward to move the parts to the right, the upper edge of the coin C will contact with the stationary cam 87, and the right end of the plate 59 will contact with the left hand end of the pawl 65. Continued movement of the plunger to the right will cause the plate 59 to remain stationary and will transfer the coin from said plate to the detent 65, which coin, due to its upper portion contacting with the cam 87, will depress the detent and cause it to disengage from the plate, which will permit the plunger to move inward to the full length of its travel, and cause the lever 33 to disengage one of the articles 65 to be vended. The position of the parts in

which the pawl 65 disengages the plate 59 is clearly illustrated in Fig. 7.

After the plunger 55 has made its full inward stroke, and the hand of the operator is removed, the spring 51 will return the parts to the position shown by Fig. 6, the plate 59 returning with the plunger because in the position shown by Fig. 7 the ball 81 is then in engagement with the recess 85 in said plate. When the plate 59 in its outward movement from the position shown by Fig. 7 strikes the left hand wall of the casing 47 the plate will stand stationary and the plunger will continue its movement to cause the ball 81 again to engage the opening 83. When the plunger moves to the left from the position shown by Fig. 7, as soon as the coin moves past the end of the detent 65 said coin will fall to the bottom of the cabinet and be caught in the coin receptacle 89.

As shown one of the bars 55 is slotted as indicated at 91 (Figs. 9 and 10) in which slot is received a lever or dog 93 pivoted to the bar at 95, while carried by the casing is a projection or stop 97 adapted to contact with the right hand end of said lever, as viewed in Fig. 10, while the opposite end of the lever is adapted to contact with the coin C when the parts have been moved to the position indicated by Figs. 7 and 10. Carried by the casing is a spring 99 the inner end 101 of which is in sliding contact with the surface of the lever 93. When the parts are in the position shown by Figs. 4 and 6, that is to say the coin receiving position of the mechanism, the spring 99 contacts with the lever 93 at the right hand side of the pivot 95, as viewed in Fig. 4, which will hold the coin contacting portion of said lever out of position to contact with the coin, thereby permitting the coin readily to move into the coin receiving slot 73. When the parts have been moved to the position shown by Figs. 10 and 7 the spring 99 will contact with the lever 93 at the side of the pivot at which the coin lies, thereby moving the lever into contact with the coin and providing that if the coin is undersized the opposite end of said lever will contact with the stop 97.

It will be observed that the detent 65 which engages the plate 59 and the detent 93 which engages the stop 97 provide for engaging the coin on diameters at right angles to each other, thereby preventing operation of the machine should an oval shaped slug be inserted.

For insuring the full stroke of the plunger 45 after the locking mechanism is released, one of the bars 55 (Figs. 4 and 6) is provided at its upper side with rack teeth 103 with which cooperates a pawl 105 pivoted at 107 and having the spring 109 connected to a fixed part of the machine for holding said pawl normally in a vertical position as shown by Fig. 6. When the plunger moves to the

right, as viewed in Figs. 6 and 7, the pawl will ride on the rack teeth and prevent return movement of the plunger until the recess 111 formed in the bar to the left of the rack teeth comes under the pawl, whereupon the pawl may be inclined in the direction opposite that shown by Fig. 7, which will permit return of the plunger.

As shown, positioned above the inner end 10 of the casing is a magnet 113 the poles of which are positioned opposite the slot 77. This will cause slugs of magnetic material to be drawn to the right, as viewed in Fig. 6, and pass through the slots 75 in the bars and discharge through the front of the machine through the slot 115. Undersized coins or slugs, which are ineffective to operate the locking mechanism, likewise will be discharged through said slot 115 when the plunger is allowed to return after being inward to cause the plate 59 to engage with the detent 65, or the detent 93 to engage with the stop 97.

Although I have described for purposes of illustration one specific embodiment of my invention it is to be understood that I am not limited thereby to its particular mechanical details, but that within the scope of the invention wide deviations may be made therefrom without departing from the spirit of the invention.

Claims:

1. Coin controlled mechanism having a plurality of locks each permitting limited movement of said mechanism, and means for controlling the open positions of said locks in accordance with different diameters of the coin comprising a lock controlling feeler for each lock movable radially of the coin, said feelers adapted to contact with the latter at different points on its periphery, and means responsive to the limited movement of said mechanism permitted by said locks for causing unlocking of the latter when a coin of predetermined diameter is inserted.
2. Coin controlled mechanism having a plurality of locks each permitting limited movement of said mechanism, and means for controlling the open positions of said locks in accordance with different diameters of the coin comprising a lock controlling feeler for each lock movable radially of the coin, said feelers adapted to contact with the latter at different points on its periphery, and a coin receiving part adapted to move the coin and feelers into contact for actuation of said locks upon said limited movement of said mechanism permitted by said locks.
3. Coin controlled mechanism having a pair 60 of locks each of which comprises a pair of parts which are relatively movable radially of the coin and contact with the periphery of the latter substantially at opposite ends respectively of diameters thereof, the coin diameter connecting the points of contact of one

of said pairs of parts being substantially at right angles to the coin diameter connecting the points of contact of the other of said pairs of parts.

4. Coin controlled mechanism having a pair 70 of locks each of which comprises a pair of parts which are relatively movable radially of the coin and contact with the periphery of the latter substantially at opposite ends respectively of diameters thereof, the coin diameter connecting the points of contact of one of said pairs of parts being substantially at right angles to the coin diameter connecting the points of contact of the other of said pairs of parts, and means forming a circular opening of substantially the diameter of the coin for permitting the coin to be inserted into operative position relative to said pairs of parts.

5. Coin controlled mechanism having, in combination, a part the motion of which is to be controlled, a plurality of locks for said part, each lock comprising an abutment member and a relatively cooperating detent member, said detent members being movable radially of the coin and distributed for respectively contacting the coin at different portions of the periphery thereof, and means forming other abutments for contacting the coin for causing the latter to control the positioning of said detent members out of the path of said abutment members.

6. Coin controlled apparatus having, in combination, a movable element, locking means for said element comprising a locking 100 member and a part for engaging the latter, said member and part being so constructed and disposed to permit limited movement of said element with said member and part out of contact, said part connected to said element for relative movement for permitting further limited movement of said element with said member and part in contact, means for contacting a coin for causing such further limited movement of said element to effect disengagement of said part and member, and other locking means for said element comprising a controlling feeler for engaging a different portion of the coin from that portion thereof engaged by said means.

7. Coin controlled apparatus having, in combination, a movable element formed for receiving a coin, a coin retaining part movable with said element and movable relative thereto into and out of coin retaining position, 115 spaced stop members for engaging said part, said stop members permitting limited movement of said element and part and moving said part into and out of coin retaining position, the stop member which moves said part out of coin retaining position being movable into-and out of engaging position with said part, means comprising a coin contacting abutment for engaging the periphery of a coin, 120 said means responsive to the limited move-

ment of said element in one direction for moving the movable stop member out of engaging position with said part, a second stop member, a second part movable with said element and movable relative thereto the position of said second part relative to said second stop member being controlled by an inserted coin, said second part being arranged for contacting the periphery of the coin at substantially ninety degrees from the portion of said periphery engaged by said coin contacting abutment.

8. Coin controlled apparatus having, in combination, a movable element, a member carried thereby for limited relative movement, a locking member for engaging said first mentioned member for permitting limited movement of said element, said first mentioned member being so constructed and disposed as to receive an inserted coin and by such limited movement transfer said coin to said locking member, means contacting the periphery of said coin for actuating said locking member into unlocked position, a second locking member and a cooperating abutment, and means contacting the periphery of said coin at a different portion thereof from that contacted by said means for controlling the disengaging of said second locking member and abutment.

9. Coin controlled apparatus having, in combination, a movable element, a member carried thereby in sliding relation thereto, a locking member cooperating with said first mentioned member, said first mentioned member acting to receive an inserted coin and to discharge said coin upon actuation of said locking member, a second locking member, and means for engaging said coin at different parts of its periphery for controlling the actuation of both locking members.

10. Coin controlled apparatus having a movable element, a fixed part carrying a stop, said movable element having a pivoted dog adapted at one end to contact with said coin and at its other end to contact with said stop, a spring carried by said fixed part, said spring being in yielding, sliding contact with said dog, said dog and stop member permitting limited movement of said element, said element having a coin receiving position in which said spring contacts with said dog at the side of the pivot thereof adjacent said stop whereby in said coin receiving position said dog is out of substantial contact with said coin, said element also having another position permitted by said limited movement in which said spring contacts with said dog at the side of the pivot thereof adjacent said coin whereby in such position said dog contacts with said coin.

11. Coin controlled apparatus having, in combination, a movable element provided with a coin receiving portion, locking means for said movable element permitting limited

movement thereof when locked, said locking means having a coin contacting part carried by said element at said coin receiving portion thereof, means for holding said coin contacting part out of contact with the coin when said movable element is at one extreme of its movement permitted by said locking means, and causing said coin contacting part to move into contact with said coin when said element is at the other extreme of said movement.

12. Coin controlled apparatus having, in combination, a movable element having a coin receiving portion, a lock for said element comprising a lock controlling feeler at said portion for engagement with the coin, said lock permitting limited movement of said element, and means actuated by movement of said element for holding said feeler out of engagement with the coin when the movable element is in position to receive a coin and for causing said feeler to contact with the coin when said element is moved from said position.

In testimony whereof, I have signed my name to this specification.
